FIG. 3

FIG. 4

FIG. 1 is a perspective view of a typewriter showing our design;

FIG. 2 is a right-hand side elevation thereof;

FIG. 3 is a rear perspective view thereof; and

FIG. 4 is a top plan view thereof.

The dominant features of the design reside in the portions shown in full lines, conventional keys and other mechanical elements being shown in broken lines in all the views.

We claim:

The ornamental design for a typewriter, as shown and described.
